UNITED STATES PATENT OFFICE.

ASA JOHNSON, OF DAYTON, TENNESSEE.

TWO-WHEEL ROAD-GRADER AND FIELD-DITCHER.

1,398,326.

Specification of Letters Patent. Patented Nov. 29, 1921.

Application filed October 13, 1920. Serial No. 416,676.

To all whom it may concern:

Be it known that I, ASA JOHNSON, a citizen of the United States, residing at Dayton, in the county of Rhea and State of Tennessee, have invented certain new and useful Improvements in Two-Wheel Road-Graders and Field-Ditchers, of which the following is a specification, reference being had to the accompanying drawings.

10 This invention relates to grading and ditching machines, and particularly to machines for grading roads and cutting ditches of the type wherein an angularly disposed scraper blade is mounted upon a

15 wheeled supporting frame having draft appliances thereon.

The general object of this invention is to provide a two-wheel road grader and field dumper especially designed to equalize the 20 load so as to give to the grader all of the qualities of a four-wheel grader, but of such a lighter construction as will permit the grader to be operated by one man and drawn by two draft horses.

25 A further object of the invention is to provide means whereby the axle may be extended so as to expand the wheel base of the machine eighteen inches and thereby permit the movement of the dirt from the edge 30 of the ditch back far enough to rehandle without slipping into the ditch.

A further object is to provide improved means whereby the blade may be manipulated or adjusted so as to cut the grade or 35 ditch at any desired depth or slope.

Another object is to provide means whereby the blade and the adjusting levers therefor may be used for jacking up one side of the machine so that the axle may be 40 extended or shortened.

A further object is to provide improved draft means for connecting the doubletree to the machine so as to equalize the draft and balance the grader and each part there- 45 of on two wheels and so eliminate the necessity for four wheels.

Other objects will appear in the course of the following description.

My invention is illustrated in the accompanying drawings, wherein:

Figure 1 is a view in top plan of a grader constructed in accordance with an embodiment of my invention, the land wheel being shown extended, the inner or retracted 55 position of said land wheel being indicated by dotted lines.

Fig. 2 is a view in side elevation of the machine as shown in Fig. 1.

Fig. 3 is a view in front elevation of the machine as herein disclosed, with the double- 60 tree slightly raised for clarity of disclosure.

Fig. 4 is a fragmentary longitudinal sectional view illustrating in detail the operative connection of a beam with the grader blade and the connection of the brace rod 65 with said beam.

Fig. 5 is a fragmentary view in perspective of the grader blade and the tilting arm carried thereby.

Fig. 6 is a fragmentary view in top plan 70 of the overlapping end portions of the axle section, the coacting locking pin being shown in separated relation.

Fig. 7 is a diagrammatic view illustrating the first operation of my improved grader 75 and wherein said grader is in a position to remove the dirt from the bottom of a ditch.

Fig. 8 is a diagrammatic view illustrating the second operation of my improved grader 80 and wherein the axle is in extended position to carry the dirt back from the edge of the ditch, and

Fig. 9 is a diagrammatic view illustrating a third operation of my improved 85 grader and wherein the wheels are in their retracted relation and wherein the device is out of the ditch and free from slipping.

Referring to these drawings, it will be seen that the axle of my improved grader 90 machine is constructed in two parallel parts 10 and 11. Each of these parts is cranked downward at its outer end, as at 12, and then outwardly extended to pass through the hub of the wheels 13. These axle bars 95 10 and 11 are flat and lay flat against each other, and the axle section 10 is shiftable with relation to the axle section 11. The axle section 11 is connected to an approximately rectangular frame 14 which includes 100 a transverse bar 15. This frame 14, as before stated, is attached to the front axle bar or section 11 but is unattached to the rear axle bar or section 10. The axle section 10 slides through three cuffs 16, and the con- 105 fronting faces of the axle sections are formed with registerable grooves 17, through which a pin 18 may be disposed to hold the axle sections in an extended or contracted position, that is, there are two of 110 these grooves in the section 10 which are adapted to register with the single groove

17 in the section 11 when the axle is contracted or expanded. The pin and these grooves hold the axle section 10 in extended position. The pin is inserted between the two parallel halves of the axle at their middle portion when closed and near the extremity of the section 10 when the axle is extended. The rectangular frame 14, which includes the cross bar 15, as before stated is fastened to the front lateral half of the parallel axle and to the tongue by means of the U-shaped strap 19 just back of where the doubletires are suspended, as will hereafter appear.

15 At each forward corner of the frame there are provided two downwardly extending brackets 20, which extend downward approximately eight inches, and attached to the lower ends of these brackets are the forward ends of rearwardly extending steel beams 21 whose rear ends are downwardly curved or bent, as at 22. The grader blade 23 is of usual shape and is longitudinally straight but is curved vertically. The rear face of 20 the blade adjacent its ends is provided with swiveled U-shaped members 24, through which pass bolts 25 which pass loosely through the ends of the beams 21. These 25 bolts form pivots upon which the grader blade 30 may swing so that the upper edge of the blade may be carried forward or rearward, thus providing for inclining the blade to different angles. Each of the bolts 25 is of a length substantially greater than the thickness 35 of the adjacent end of the beam 21 so that the blade 23 may be shifted laterally of the machine to a limited extent as the occasions of practice may prefer. The beam 21, however, is maintained in substantially a 40 fixed point of connection with the pin 25 by the washers 25^a placed on either side of the beam 21 as the occasions of practice may prefer. When it is desired to slightly shift the 45 blade 23 in a direction laterally of the machine, the pin 25 is removed and the washers 25^a readjusted as the requirements of practice may necessitate.

It is also preferred that the free end portion of each of the beams 21 coacting with a pin 25 be bent in a lateral direction to one side of the beam 21 so that the pin 25 may be parallel to the longitudinal center line of the blade 23.

The central parts of the curved portions 55 22 of the beams 21, and particularly at the points of greater curve, are connected by the brace or stay rod 26 which acts to maintain the grader beams 21 in a substantially horizontal position and substantially in parallelism whereby said beams 21 are steadied, 60 and also whereby the blade 23 may move freely on the bolts 25 as required.

65 Mounted upon the frame 14 on each side of the frame are the U-shaped racks 27, and pivotally mounted upon these racks are the

levers 28 and 28^a, these levers being pivoted to vertical links 29 which extend downward and embrace the beams 21 and are pivoted thereto. It will be noted, of course, that one of the beams is shorter than the other beam 70 so that the scraper is held at an angle of approximately 45° to the line of draft and that, therefore, one of the links 29 engages with the right hand beam adjacent the scraper 23, while the other link 29 is connected to the 75 left hand beam a considerable distance ahead of the scraper. The levers 28 and 28^a are provided with the usual hand operated latching bolts 30 engaging the racks whereby the levers may be held in any adjusted position. 80 It will be seen that by operating these levers, the scraper blade may be raised or lowered as a whole or one side of the scraper blade may be shifted downward below the other side of the scraper blade. 85

The scraper blade is to be tilted by means of a lever 31 which is pivotally mounted upon an arcuate rack 32 and has a hand operated bolt 33 engaging this rack to hold the lever in any adjusted position. This lever at 90 its lower end is connected by a link 34 to an arm 35 extending upward from and attached to the upper edge of the scraper blade, and thus it will be obvious that as the lever 31 is shifted, the blade will be tilted to a greater 95 or less extent. This lever, therefore, controls the angle of the grader blade with the ground or road bed to be graded, and when moving the grader over the road to a new location, the blade is shifted forward, that is, tilted 100 forward, so as not to allow the blade to touch the traction wheel 13^a. By shifting the blade to a vertical position and pressing one end of the blade downward by means of the lever 28, the right hand end of the grader 105 may be lifted, thus lifting wheel 13^a off the ground and jacking it up so that the axle section 10 may be extended or shortened, as desired. The levers 28 and 28^a are used for controlling the depth of cut and the angle 110 of the blade to the horizontal, thus permitting the blade to be adjusted for ditching or for grading roads.

Connected to one of the beams 21 and preferably adjacent to one end of the brace or stay rod 26 is a chain 36 which extends laterally and upwardly and is connected to a hook 37 carried by the front section of the axle. Also connected to the left hand beam 21 at its point of connection to the brace 26 is a chain 36^a which extends laterally and forwardly and is connected to a hook 37^a carried upon the forward section. These chains act to prevent any lateral swinging movement or strain on the beams 21 caused by the inclination of the blade to the line of draft. They act, when the grader blade is lowered in cutting the dirt, to keep the grader blade from extending or shifting out beyond the landing wheel 13^a and cutting 130

into the bank and cause the grader blade to cut in advance of the landing wheel so as to cut a way or track in which the land wheel may follow.

- 5 Attached to the cranked extremity 12 of the section 10 is a chain 38, which extends forward and is connected to the front right hand corner of the grader frame at the corresponding bracket 20, and this chain 38 10 acts to distribute the load evenly on the grader and team. Without this chain, the tongue of the grader would be pulled toward the bank. This chain is idle only when the axle is contracted.
- 15 The grader blade, which is approximately five feet long, is disposed at an angle of 45° to the line of draft, and has its forward point just in front of the land wheel under ordinary circumstances and cuts a track for 20 that wheel to travel in. The angle of the blade is such and the blade is so placed with relation to the other parts of the grader that it sheds the dirt off its rear end like the mold board of a plow, completely removing the 25 dirt from the point of the grader blade a distance of four feet. This blade is so attached to the levers 28, 28^a and 31 that the angle of the blade both vertically and laterally may be changed at the will of the operator so as to suit the condition of the work 30 to be accomplished by the grader.

It will be understood that the clevises or members 24 are so connected to the grader blade that the blade may be moved up as the 35 point of the blade is worn off, thereby increasing the life of the grader by many years. The doubletree 39 is swung beneath the tongue by means of eight-inch chains 40, and is disposed on the same level as the forward ends of beams 21 where they join the 40 brackets 20. From a common clevis 41 there extends rearwardly two stay chains 42 to a point fourteen inches back at the ends of the beams 21, and these chains are hitched 45 to the beams at this point so as to distribute the draft of the grader. These chains give to this grader a perfect poise and balance as though it had four wheels and take the weight of the tongue from the necks of the 50 horses and give to each side of the grader an even draft, inasmuch as these chains tend to pull down the rear end of the machine and apply a draft thereto which will tend to raise the tongue. These chains apply the 55 draft to the beams 21 where it is particularly needed. A seat 43 is attached to the rear end of the tongue in the usual manner.

By forming the axle in two sections 10 and 11 and having the section 10 shiftable 60 with relation to the section 11, the axle may be extended to one side of the line of draft a distance of eighteen inches, and by this means the dirt that has been brought from the bottom of the ditch four feet by means 65 of the blade 23 may be moved an additional

eighteen inches, and then by shortening the axle in the manner heretofore described, the wheel is immediately turned to its original position and then the bar may be moved four feet from the top of the ditch without the 70 wheels slipping back into the ditch.

I claim:

1. A grader and ditcher of the character described comprising an axle, traction wheels mounted thereon, a tongue connected 75 to the axle, a frame attached to the axle and extending forward therefrom and connected to the tongue, downwardly extending brackets on the forward corners of the frame, scraper supporting beams operatively 80 connected to the extremities of the brackets and extending rearward therefrom, a scraper blade tiltably mounted upon the beams, oppositely disposed levers operatively connected to the beams to raise or depress them, 85 means for holding the levers in adjusted positions, and a lever operatively mounted upon the frame and having operative connections to said blade whereby the blade may be tiltably adjusted. 90

2. A grader and ditcher of the character described comprising an axle, traction wheels mounted thereon, a tongue connected to the axle, a frame attached to the axle and extending forward therefrom and connected to the tongue, downwardly extending brackets on the forward corners of the frame, scraper supporting beams operatively 95 connected to the extremities of the brackets and extending rearward therefrom, a 100 scraper blade tiltably mounted upon the teams, oppositely disposed levers operatively connected to the beams to raise or depress them, means for holding the levers in adjusted positions, a lever operatively mounted 105 upon the frame and having operative connections to said blade whereby the blade may be tiltably adjusted, and chains operatively connected to the rear ends of the beams and crossing each other and operatively connected to the axle. 110

3. A grading and scraping machine of the character described including a supporting frame, an axle in two sections, one of said sections being fast on the frame, the 115 other section being laterally adjustable relative to the frame and the first named section, supporting wheels mounted upon said axle sections, beams pivotally connected at their forward ends to the forward end of 120 the frame and extending to a point rearward of the axle and downwardly turned, one of said beams being longer than the other, a scraper blade mounted upon the rear ends of the beams and extending at an 125 angle to the line of draft, and means connected to the beams whereby they may be independently vertically adjusted.

4. A grading and scraping machine of the character described including a support- 130

ing frame, an axle in two sections, one of said sections being fast on the frame, the other section being laterally adjustable relative to the frame and the first named section, supporting wheels mounted upon said axle sections, beams pivotally connected at their forward ends to the forward end of the frame and extending to a point rearward of the axle and downwardly turned, one of said beams being longer than the other, a scraper blade mounted upon the rear ends of the beams and extending at an angle to the line of draft, and means connected to the beams whereby they may be independently vertically adjusted and including racks mounted upon the frame on each side thereof, levers pivotally mounted upon the racks and having latches to engage the racks and hold the levers in adjusted position, and links operatively connected to the levers and operatively connected to the frame.

5. A grading and scraping machine of the character described including a supporting frame, an axle in two sections, one of said sections being fast on the frame, the other section being laterally adjustable relative to the frame and the first named section, supporting wheels mounted upon said axle sections, beams pivotally connected at their forward ends to the forward end of the frame and extending to a point rearward of the axle and downwardly turned, one of said beams being longer than the other, a scraper blade mounted upon the rear ends of the beams and extending at an angle to the line of draft, means connected to the beams whereby they may be independently vertically adjusted and including racks mounted upon the frame on each side thereof, levers pivotally mounted upon the racks and having latches to engage the racks and hold the levers in adjusted position, links operatively connected to the levers and operatively connected to the frame, the scraper blade being tiltably connected to the rear ends of the beams and having an arm extending upward from the blade, a lever mounted upon the frame, means for holding the lever in adjusted position, and a link operatively connecting said lever to the arm.

6. A grading and scraping machine including a supporting frame, an axle formed in two sections, one of said sections being fast on the frame, the other section being laterally adjustable relative thereto, wheels mounted on the ends of the axle sections and supporting the machine, beams pivotally connected to the forward corners of the frame and extending rearward of the axle, one beam being longer than the other, an angularly disposed scraping blade carried by said beams, means mounted upon the frame for vertically adjusting each of said

beams independently of the other, and a chain connected to the outer end of the movable axle section and to the forward end of the frame and rendered taut when the axle section is shifted to increase the space between the wheels.

7. A grading and scraping machine including a supporting frame, a single axle therefor having cranked ends, wheels mounted upon the ends of the axle, said axle being formed in two sections, one of said sections being fixed to the supporting frame, the other section being shiftable relative thereto whereby the wheel base may be contracted or expanded, brackets extending downward from the forward corners of the supporting frame, beams pivoted to said brackets and extending rearwardly therefrom and having their rear ends downwardly bent, said beams being of unequal length, the shorter beam being adjacent the supporting wheel on the shiftable axle section, a brace operatively connected to the longer beam adjacent the upper end of the scraper blade and connected to the shorter beam adjacent the lower edge of the scraper blade, crossed chains, one chain being attached to the fixed axle section adjacent its outer end and extending rearward and being connected to the rear end of the shorter beam adjacent the upper edge of the blade, the other chain being connected to the rear end of the longer beam adjacent the upper edge of the blade and extending forward and attached to the end of the fixed axle section adjacent the supporting wheel mounted upon the shiftable axle section, manually operable means mounted on the supporting frame for independently raising or lowering either one of the beams, and means mounted on the supporting frame for tilting the blade with relation to a vertical plane.

8. A grading and scraping machine of the character described including an axle cranked at its ends, supporting wheels mounted on the axle, said axle being formed in two sections, one of said sections being shiftable adjustable upon the other section, a scraper blade swung beneath the axle, and manually operable means for depressing the scraper blade to thereby raise the wheel of the adjustable axle section off the ground and support the machine with the wheels of the adjustable axle section off the ground to thereby permit the axle section to be adjusted.

9. A grading and scraping machine including an axle cranked at its ends, supporting wheels mounted thereon, a rectangular supporting frame attached to the axle and extending forward thereof, a tongue attached to the axle at its rear end and at its forward end operatively connected to the supporting frame, brackets extending downward from the forward corners of the frame,

- beams connected at their forward ends to said brackets and extending rearward therefrom and then downward, a scraper blade carried upon said beams and angularly disposed with relation to the line of draft, 5 manually operable means for raising or lowering the rear ends of the beams to raise or depress the scraper blade, a doubletree swingingly connected to the scraper blade 10 and disposed beneath the rear portion of the tongue and swingingly connected thereto forward of the front end of said frame and on a level with the forward ends of said beams, and stay chains extending rearward 15 from a point on said doubletree and engaged with the rear ends of the scraper supporting beams.
10. A grading and scraping machine including an axle cranked at its ends, supporting wheels mounted thereon, a rectangular supporting frame attached to the axle and
- extending forward thereof, a tongue attached to the axle at its rear end and at its forward end operatively connected to the supporting frame, brackets extending downward from the forward corners of the frame, beams connected at their forward ends to said brackets and extending rearward therefrom and then downward, a scraper blade carried upon said beams and angularly disposed with relation to the line of draft, 25 manually operable means for raising or lowering the rear ends of the beams to raise or depress the scraper blade, and a draft evener operatively connected to the tongue disposed 30 on a level with the forward ends of the beams, and flexible connections between said draft evener and the rear ends of the beams. 35

In testimony whereof I hereunto affix my signature.

ASA JOHNSON.
